UNITED STATES PATENT OFFICE.

JOSEPH S. STRICKLER, OF ALIQUIPPA, PENNSYLVANIA.

CHANGE-MAKER.

1,110,159.

Specification of Letters Patent.

Patented Sept. 8, 1914.

Application filed September 30, 1913. Serial No. 792,664.

To all whom it may concern:

Be it known that I, JOSEPH S. STRICKLER, a citizen of the United States, residing at Aliquippa, in the county of Beaver and State of Pennsylvania, have invented certain new and useful Improvements in Change-Makers; and I do hereby declare the following to be a full, clear, and exact description of the invention, such as will enable others skilled in the art to which it appertains to make and use the same.

This invention relates to new and useful improvements in change makers and has for its object the provision of a device which will change coins of any denomination from one dollar to ten cents.

Another object of the invention is the provision of such a device which when making change will retain five cents from the total amount placed therein.

Still another object of the invention is the provision of such a device which may be used at sub-ways, and theater entrances, on street cars and in all places where it is desired that change be made quickly and a certain amount taken out.

A further object of the invention is the provision of such a device which is adapted to prevent dishonesty among the employees of such corporations as street car companies and the like.

With the above and other objects in view I will now proceed to describe the invention, in the following specification and accompanying drawings, in which,

Figure 1 is a perspective view of my improved change maker showing the same as it would appear when in use, Fig. 2 is a sectional view of this improved change maker as the same would appear with the side plate removed, Fig. 3 is a fragmentary view of Fig. 2, showing the same with the lever in the position for changing the coins and also the sweep operating mechanism in detail, Fig. 4 is a transverse sectional view of the change maker showing the coin ejectors in plan, Fig. 5 is a fragmentary view of Fig. 4 showing the coin ejectors in their operative positions, Fig. 6 is a plan view of the money drawer showing the chute on which the money falls after having attained a predetermined height in the stacks, Fig. 7 is a sectional view taken on line 7—7 of Fig. 6, Fig. 8 is a sectional view taken on line 8—8 of Fig. 6. Fig. 9 is a detail view of the

chutes showing the coin stacks at the bottom, Fig. 10 is a detail perspective view of one of the stacks showing the ejector in its forward position, Fig. 11 is a detail sectional view of the slot showing the magnet 60 for removing spurious coins, Fig. 12 is a sectional view taken on line 12—12 of Fig. 11, and Fig. 13 is a horizontal sectional view of one of the plungers for forcing coins into the chutes leading to the stacks.

Reference being had more particularly to the drawings 1 represents the base of my improved coin changing machine having secured thereto and extending upwardly therefrom the front wall 2, the rear wall 3 and the right and left side walls 4 and 5, respectively. A suitable partition wall 6 extends transversely across the casing thus formed, and separates the bottom of said casing into two separate compartments. 75 This wall 6 terminates a short distance from the bottom wall 1 and is provided with a suitable cover 7 which extends, as illustrated in Fig. 2, to the front wall of the casing. A suitable extension 8 is formed integrally 80 with the wall 6 intermediate its width and is adapted to act as a rest for the chute 9 through which the coins after leaving the stacks are adapted to pass on their way outwardly. A suitable cash drawer 10 is slidably mounted in the receptacle formed between the walls 1, 2, 6 and 7 and is adapted to receive the coins which are forced from the tops of the stacks after they have attained the predetermined height.

The cover 7, above referred to, is provided with suitable grooves 11 in which a suitable longitudinally extending tongue 12 formed on the under side of the ejector plate 13 is slidably mounted. This ejector plate 95 is preferably provided on its upper face, at suitable intervals, with the upstanding projections 14 and at its forward end with the coin ejecting reduced portion 15. This coin ejecting reduced portion is provided with the outstanding ears 16 which are provided to more firmly engage the coins when the same are being forced from their position beneath the stacks.

Suitably secured to the bottom of the casing 1 and extending upwardly therefrom I preferably provide the ear 17 to which is pivotally secured the lever 18 as shown at 19. The upper end of the lever 18 is provided with a suitable handle 20 which ex-

2

5 tends through the slot 21 formed in the top of the casing, as is clearly illustrated in Fig. 2. A suitable link 22 is pivotally secured as shown at 23 to the lever 18 and extends toward the front of the casing for a short distance. The free end of this link 22 is spaced from the center of the casing as clearly illustrated in Fig. 2 and pivotally connected to the rocker 24 as shown at 25.

10 This rocker 24 is pivoted intermediate its length as illustrated at 26 and extends downwardly as shown. The lower end of this rocker is provided with an aperture through which one end of the link 27 is adapted to extend. The opposite end of said link is pivotally connected, as illustrated at 28, to the upstanding member 29, which is formed on the bar 30, the use of which will be more fully hereinafter described. The 15 bar 30, above referred to, is slidably mounted in the casing and provided intermediate its ends with the off-set portions 31 intermediate which are formed the recesses 32.

20 A suitable longitudinally extending bar 25 33, which is supported intermediate the wall 6 and the wall 2, is provided and has pivotally secured thereto, as shown at 34, the ejector levers 35 which coöperate with the upstanding portions 14 formed on the ejector plates in forcing the coins outwardly. These levers 35 are adapted to rest in the recesses formed in the bar 30 as clearly illustrated in Figs. 2 and 4, and are adapted to be returned to their normal position by said bar 30 after the change has been made. A lever 36 which is pivotally secured to the bar 33, as illustrated at 37, is adapted to coöperate with the upstanding portions 38 which correspond with the upstanding portions 14, formed on the ejector plates 13.

35 The coin stacks represented generally by the characters A, B, C and D are preferably held in position by means of the cylindrical casings 39, 40, 41 and 42, respectively. The upper ends of these casings terminate as shown in the chute, illustrated in Fig. 9. It will be clearly seen that the chute indicated by the numeral 43 is not provided at its lower extremity with a coin stack casing, 40 but terminates in a passage 44 which opens directly into the money drawer.

45 The top of my improved casing, indicated generally by the numeral 45 is provided with the slot 46 which terminates at its inner end in the vertically extending slot 47. This slot 47 is formed intermediate the plungers 48, 49, 50, 51, 52, 53, 54, 55, 56 and 57, which are slidably mounted across the casing. The plungers 48, 50, 52, 54 and 56 are 50 provided with the extensions 58, 59, 60, 61 and 62, respectively, which are so shaped as to conform with the contour of the coin which is adapted to be inserted therein. Thus, it will be seen that the coins of a 55 smaller denomination will fall downwardly

until one of the projections will engage said coin, thereby causing the same to lodge in the recess of the proper denomination.

After the coin has reached its proper recess the lever 18 is pushed, thus causing the 70 same to swing on its pivot as indicated by the dotted lines and forcing the plungers 48, 50, 52, 54 and 56 toward the opposite set of plungers 49, 51, 53, 55 and 57. Thus, it will be seen that the plunger of the first mentioned set, against which the coin is lodged will through the coöperation of the coin force the opposite plunger rearwardly as will be obvious upon reference to the drawing. Each of the plungers 49, 51, 53 and 80 57 is provided with a suitable projection 60' which is adapted to coöperate with the set of levers 61' which are pivoted as shown at 62'. The ends of the levers opposite the elongated ends are extended as shown in 85 Fig. 2, and are adapted to engage the levers 35 as will be clearly seen upon referring to Fig. 4.

To more fully describe the operation of the device I will assume that a party is endeavoring to change a dollar. It will be apparent that said coin will slide through the slot 46 until it reaches the slot 47 when it will turn into a vertical position and rest against the projection 58 which is 95 formed on the plunger 48 and in the space formed between the forward end of the plunger 48 and the rear end of the plunger 49. The lever 18 is then pushed to the position illustrated in dotted lines and it 100 will be obvious that said coin will be forced against the lever 49, thus causing said lever to slide forward and carry the levers 61' into the position illustrated in the dotted line. In this operation the free end of the 105 levers 61' will engage the foremost lever in the set referred to by the numeral 35, thus, it will be seen that said foremost lever will be swung on its pivot 34 and assume the position shown in Fig. 5, thereby forcing 110 the ejector plates 13 outwardly and causing the bottommost coins on each of the stacks to be forced toward the chute referred to by the numeral 9. The only ejector plate 115 which is not operated at this time is the one which slides beneath the stack of five cent pieces and the only time that this ejector plate is put in operation is when a dime is to be changed, at which time the remainder of the ejector plates remain immovable.

A suitable lever 62'' is pivotally mounted as shown at 63 on a suitable support 64. This lever is pivotally secured to the link 22, as shown at 65. The free end of said lever has secured thereto a suitable link 66, the free end of which is adapted to extend through a slot 67 formed in the extension 68 carried by the sleeve 69 which is secured to a shaft 70. This shaft 70 extends transversely of the casing and is journaled as 120 125 130

shown at 71 to the sides thereof. At suitable points adjacent each end of the shaft I preferably secure sleeves having formed integral therewith the upstanding portions 72, the free ends of which are provided with apertures through which the ends of the links 73 are adapted to extend. This link 73 is provided at its free end with a suitable hook 74 which is adapted to extend through an aperture formed adjacent the ends of the sweep 75. This sweep is slidably mounted in suitable guides 76 formed at the ends of the coin stacks, as is clearly illustrated in Fig. 9. Thus, it will be seen that when the 10 coins attain their predetermined height the sweep through the action of the lever and link connections will force the topmost coin from the stack and onto a chute 77 which terminates in the enlarged portion 78 near the innermost end of the cash drawer. It will be apparent that these lever and link connections will be operated at every operation of the machine and the sweep will be caused to carry the top coins rearwardly and 25 it will be apparent that a predetermined height of the coin stacks will be maintained.

Suitably secured to the mouths of the casings and the chute 43 and coöperating therewith I preferably provide the ejectors 79, 30 which preferably comprise the casings 80, in which the plungers 81 are slidably mounted. These plungers 81 are provided at their forward ends with the cam faces 82 and at their rear ends with the stems 83 around which the coil springs 84 are adapted to extend. These coil springs are preferably of the compression type and the rear ends of the same are adapted to abut the rear walls of the casings 80 and the forward ends 40 are adapted to abut the rear walls of the plungers 81. Thus it will be seen that said plungers are normally held in their extended position and thereby normally tend to force the coin which comes into registration with the mouths of the casings 39, 40, 41, and 42 45 and the mouth of the chute 43 outwardly and into said casings and chutes. The slot 46 is provided intermediate its length with the depression 85 which is formed at one 50 side of said slot and in direct alinement with the recess 86 in which a suitable magnet 87 is adapted to be secured. This recess 86 terminates at its under side in a suitable slot 88 which extends as illustrated in Fig. 55 12 to the side of the top referred to by the numeral 45.

It will be apparent from the foregoing that when it is desired to make use of my improved money changer a coin of any suitable denomination is placed in the slot and the same will fall to the desired point. Upon operation of the lever 18 it will be clearly seen that the plungers 48, 50, 52, 54 and 56 60 will be forced over thereby closing the slot 47 and forcing the coin against one of the

plungers 49, 51, 53, 55, or 57 which operation will cause one of the levers 61' to swing on its pivot 62', thereby forcing the levers 35 in the opposite direction and eject the proper coins from their positions beneath the stacks through the medium of the ejector plates 38. Upon returning the lever 18 to its normal position it will be apparent through the medium of the link 22, the rocker arm 24 and the bar 30 that the levers 35 and 61' 70 will be returned to their normal position and the machine will be again ready for operation. At the same instant during the operation of the levers the sweeps 75 will pass across the tops of the coin stacks and sweep 75 the uppermost coin from its position thereon and into the chute 77, thereby conveying said coins to the cash drawer and preventing the casings 39, 40, 41 and 42 from becoming 80 clogged. Thus, it will be seen that the coin stacks will be maintained at a predetermined level and the passages thereinto kept 85 clear at all times.

While in the foregoing I have shown and described the preferred embodiment of my 90 invention I wish it to be understood that I may change the specific arrangement and combination of parts without in any way departing from the spirit and scope of my invention as defined in the claims appended 95 hereto.

What is claimed is:—

1. A device of the character described comprising a casing, a wall extending transversely through said casing, a lever hingedly secured adjacent said wall, two sets of plungers slidably mounted on said wall, one set of plungers being pivotally connected to the lever, projections formed on each of the plungers in the second mentioned set, levers 100 pivotally mounted adjacent the lower edge of the wall, each of said levers being of a different length, a second set of levers coöperating with the first mentioned levers, ejectors slidably mounted adjacent the bottom 105 of the casing, projections secured to each of said ejectors, coin stacks in direct alinement with the forward ends of the ejectors, means to conduct the coins to their respective stacks, the second set of levers 110 being adapted to coöperate with the projections on the ejectors and force the bottom most coin from its position beneath the coin stacks when the device is operated.

2. In a device of the character described 115 a casing, coin assorting plungers slidably mounted in said casing, lever operating plungers directly opposite the coin assorting plungers and slidably mounted in said casing, coin conducting tubes adjacent the 120 lever operating plungers, coin stacks at the lower ends of said tubes, a plurality of levers pivotally secured to said casing and adapted to be operated by the plungers, levers coöperating with the first mentioned 125 130

levers, ejectors operated by the second mentioned levers and adapted to force the bottom-most coins from their position in the stacks, a cash drawer slidably mounted in 5 the bottom of the casing, and a sweep adapted to be operated on each operation of the device and cause the topmost coin in each of the coin stacks to be deposited in the cash drawer after said stacks have attained a 10 predetermined height.

3. In a device of the character described a casing, means in said casing to assort coins of different denominations, coin conveying tubes coöperating with the assorting means, 15 coin stacks at the lower ends of the coin conveying means, means operated by the assorting means to eject the bottom-most coins from their positions in the coin stacks, a cash drawer slidably mounted in the casing, 20 a sweep adapted to sweep the top most coins from their positions in the coin stacks after said stacks have attained a certain height, and means to operate said sweep upon each operation of the device.

4. In a device of the character described a casing, coin assorting means in said casing, coin conveying tubes coöperating with the coin assorting means, coin stacks at the lowermost extremities of the coin conveying 30 tubes, means to eject the lowermost coins from their positions in the stacks, a cash drawer slidably mounted in the casing, a sweep adapted to force the topmost coins from their positions on the stacks after they 35 have attained a certain height, an operating lever pivotally secured to the casing and extending upwardly through a slot therein, and means secured to said operating lever to cause the sweep to operate when the device 40 is in use.

5. In a device of the character described a casing, coin assorting means mounted in said casing, coin stacks mounted in said casing and coöperating with the coin assorting 45 means, coin ejectors slidably mounted beneath the coin stacks and adapted to force the bottom-most coins from their positions therein, a sweep slidably mounted across the top of the coin stacks, a cash drawer slidably 50 mounted in the casing, said sweep being adapted to sweep the topmost coins from their positions on the coin stacks and into the money drawer after the same have attained a predetermined height, a train of 55 levers and links adapted to operate said sweep and means to return the ejectors to their normal positions upon the completion of each operation.

6. In a device of the character described 60 a casing, a lever pivotally secured to the interior of said casing and extending through a slot formed in the side thereof, coin assorting plungers slidably mounted in said casing and pivotally secured to the lever, lever operating plungers slidably mounted in the

casing directly opposite the coin assorting plungers, a plurality of levers pivotally secured to the casing, and adapted to be operated by the lever operating plungers, extensions formed at the lower ends of said 70 levers, a second set of levers pivotally secured to the casing and adapted to swing in a horizontal plane, ejector plates slidably mounted in said casing and adapted to be operated by the second set of levers, coin 75 conducting tubes adjacent the lever operating plungers, coin stacks at the lower ends of the conducting tubes, said coin stacks having slots at their upper and lower extremities, the slots in the lower extremities being 80 adapted to receive the ends of the ejectors when the device is in use, a sweep slidably mounted in the uppermost slot, a cash drawer slidably mounted in the casing, means connected with the first mentioned 85 lever adapted to return the ejectors to their normal position after each operation, and means to slide the sweep across the tops of the coin stacks when the device is in use.

7. In a device of the character described a 90 casing having a coin receiving slot in the upper end thereof, and a notch adjacent the coin receiving slot, a plurality of plungers slideable transversely through the casing, each of said plungers being of different 95 length and having extensions formed thereon, said extensions being shaped to conform to the contour of coins of different denominations, a second set of plungers, slideable in the casing and in direct alinement with the 100 first mentioned plungers but spaced therefrom, a plurality of levers pivotally mounted in the casing, lateral projections formed on the second mentioned plungers and adapted to form abutments for the elongated ends of the levers, a lever pivotally secured to the casing, said lever also being pivotally secured to each of the first mentioned plungers and operable through the 105 second mentioned slot in the casing, a second set of levers pivotally mounted in the casing at right angles to the first mentioned set of levers and adapted to be operated by the short ends thereof, ejector plates slideable through the casing and adapted to be operated by the second set of levers, a plurality of coin stacks having slots at their lower 110 ends through which the ejector plates slide, and a chute to receive the bottommost coin from the stack when the device is operated. 115

8. In a device of the character described, the combination with a casing, having a plurality of coin stacks, coin collecting plungers slideable in the casing, and coin ejecting means operated by the coin collecting plungers, of a lever pivotally mounted in the casing, and adapted to operate the coin collecting plungers, a sweep slideable across the coin stacks to force the topmost coins therefrom after the said stacks have attained a 120 125 130

predetermined height, and means connected to the lever to operate said sweep upon each operation of the device.

9. In a device of the character described a casing, having a coin receiving slot therein, a plurality of plungers of different lengths slidably mounted in the casing and adapted to distribute coins of different denominations according to their size, a plurality of 5 plungers coöperating with the first mentioned plungers slidable in the casing, a plurality of coin stacks having coin receiving chutes communicating therewith, the open ends of said coin chutes being covered by 10 the second mentioned sliding plungers, a lever pivotally secured to the casing and to each of the coin collecting plungers whereby the plungers may be operated, and an automatic 15 ejector at the mouth of each of the coin chutes to force the coins into the respective chutes after the second mentioned plungers have been operated.

10. In a device of the character described a casing, a plurality of coin collecting plun-

gers slidable through the casing, a plurality 25 of plungers coöperating with the coin collecting plungers slidable in said casing, and in direct alinement with the coin collecting plungers, coin stacks within the casing, coin chutes coöperating with the coin stacks, the 30 open ends of the coin chutes, and a spring 35 tive relation with the coin collecting plungers and the second mentioned plungers, a cylindrical member secured within the casing adjacent the lower edge of each of the open ends of the coin chutes, and a spring 40 pressed plunger having a tapered outer end extending into the path of the coins as they pass in front of the coin chute mouths, and adapted to force the lower edges of the coin into the coin chute when the device is operated.

In testimony whereof I affix my signature in presence of two witnesses.

JOSEPH S. STRICKLER.
